UNITED STATES PATENT OFFICE.

WILLIAM H. G. GEAKE, OF KILLARA, NEAR SYDNEY, NEW SOUTH WALES, AUSTRALIA, ASSIGNOR TO WALTER RUTHERFORD, OF LONDON, ENGLAND, AND JOHN BAIN, OF OTTAWA, CANADA.

DISPENSING CONTAINER FOR PLASTIC SUBSTANCES.

Application filed November 10, 1925, Serial No. 68,225, and in Great Britain September 22, 1925.

This invention relates to dispensing containers for plastic substances and particularly to that type of container from which the contents are expelled by torsional diminution in the volume of the container.

The principal objects of the invention are to construct a torsionally collapsible container in which shortening of the container along the axis of twist does not occur and therefore does not have to be compensated for; to produce a dispensing container in which the torsional fulcrum adjacent the discharge end is free from torsional stress until substantially the entire contents of the container have been expelled, therefore avoiding imprisonment of a portion of the contents between upper and lower twisted portions of the container; to provide a container of the class described in which the torsional stress is directed in radial lines lying in planes transverse to the axis of twist, which progressively approach the discharge end of the container so that the body or contents diminishes only in a depth direction until substantially all of the contents are expelled, the twisting of the container taking place entirely below the body of contents; to construct a dispensing container including relatively rotatable cooperating rigid members forming a chamber in which is a torsionally emptied sack, preferably of non-elastic material, anchored to both members and twisted by rotating said members, and to provide for the adhesion of lateral portions of said sack to corresponding parts of one of said members, preferably that having the discharge opening, the sack being progressively torn away from its adhesive bond with said member when relative rotation is imparted to said members.

Other objects will appear as the following description of illustrative embodiments thereof proceeds.

While a dispensing container such as the present invention contemplates may be used for holding or dispensing any desired plastic substance whatsoever, such as face creams or the like, it is to be regarded, in considering the present illustrative disclosure, as particularly suitable for containing and dispensing of motor grease.

In the drawings:—

Figure 1 is a vertical section through a

container embodying the principles of my invention.

Figure 2 is in part a plan view and in part a transverse section of the same.

Figure 3 is a vertical section taken at right angles to that shown in Figure 1 and showing the torsionally collapsible sack in substantially collapsed condition.

Figure 4 is a vertical section through another form of container embodying the invention and showing a slightly modified means for securing the sack to the discharge nozzle of the container.

Figure 5 is a section taken along the line 5—5 of Figure 4.

Figure 6 is in part a vertical section and in part an elevation of still another form of the invention.

Figure 7 is a plan view of the anchoring disk for securing the mouth of the sack to the lower of the relatively rotatable members.

Figure 8 is a vertical section through the lower portion of still another form of container in which a key takes the place of one of the dished members shown in the previous embodiment.

Figure 9 is a plan view of the key shown in Figure 8, viewed from beneath.

Referring now in detail to the several figures and first advertiring to that form of the invention shown in Figures 1, 2 and 3, 85 1 and 2 represent telescoped members, freely relatively rotatable, the former being regarded as the top and having a discharge nozzle 3. Said members together form a chamber in which is housed a sack 4, the latter consisting preferably of flexible but non-elastic material, such as muslin or other fabric, certain grades of paper or any suitable substance. Said sack is made of such size that, when filled with the plastic contents which the container is designed to dispense, it fits the chamber between the members 1 and 2. The bottom of the sack is secured to the member 2 by means adapted to impart a torsional stress to the 100 sack when the members are relatively rotated, but to avoid the possibility of a pivotal action between the sack and said member, which latter action would constitute a defect militating against the transmission of 105 the torsional stress to the sack. In the pres-

ent instance the fixing means includes a metallic disk 5 bearing against the inner face of the bottom of the sack and riveted in two places as at 6 and 7, through the 5 bottom member 2. The upper or open end of the sack may be secured adjacent the nozzle in any suitable fluid tight manner, one expedient being shown in Figure 1 in which the top member is provided with a circular 10 opening 8 through which projects a bushing 9 having a flange 10 at its lower end underlying the edges of the opening 8, said bushing constituting the discharge nozzle. The open mouth of the sack is brought around 15 the flange 10 into contact with the exterior of the bushing 9, being held in place by a resilient ring or washer 11 which surrounds the mouth of the sack and the bushing 9 and preferably fits within the opening 8. A cap 20 12 screws upon the bushing 9 and holds the flange 10, the marginal edge of the sack, the top member 1 and the ring 11 in compressive relation. This suffices to render the container leak-proof during shipment or 25 when it is not in use. When the contents are to be expressed from the container the cap 12 is removed, and the pressure of the contents against the flange 10 then suffices to maintain a tight joint between the parts.

30 The joint between the sack and nozzle is preferably not depended upon to resist the torsional stress imparted to the sack by rotation of the bottom member 2. Instead, the side walls of the sack and, if desired, 35 the top wall thereof, are caused to adhere to the corresponding walls of the member 1 by the application of any suitable adhesive to said walls or to said sack. In the present instance a coating of suitable substance such as shellac, the same being designated by the reference character 13, is applied to the interior lateral and top surfaces of the member 1 before the sack is put in place.

40 In operation, when the top member 1 is grasped and the bottom member 2 rotated relatively thereto a twisting stress is imparted to the lower portion of the sack which is resisted by the adhesive bond between the 45 lateral wall of the sack and that of the member 1, said bond giving way first adjacent the bottom of the container where the torsional stress is directed in radial lines in the plane of the bottom, said sack progressively coming away from the side wall of the container as the twisting of the lower portion thereof continues, that part of the sack in contact with the bottom of the contents thereof maintaining a substantially 55 flat shape in a plane transverse to the axis of twist but progressively moving upwardly toward the discharge end of the container, until the contents thereof are substantially all expelled. The condition of the sack at 60 the time of substantially complete expul-

sion is shown in the upper part of Figure 3, and an intermediate position of the sack is shown in the same figure in dotted lines.

It is to be understood that the torsional stress is borne entirely by the adhesive between the sack and member 1 throughout the act of expulsion of the contents thereof, the joint adjacent the nozzle being entirely relieved from stress. The adhesive also functions to localize the twist at the lower end of the sack so that there is no risk of the contents of the sack or a portion thereof being imprisoned between twists simultaneously formed both at the upper and lower ends of the sack, such as might ordinarily occur in the absence of the novel features of my invention.

It is possible to obtain considerable pressure at the nozzle in the expelling operation practiced in using the container since the 85 mechanical advantage is substantially the ratio between the radius of the lower rotatable member, and that of the diameter of the twisted portion or neck of the sack. When it is realized that a material such as 90 fabricated cloth or paper is weak only in the direction of shearing stress but enormously resistant to tension, and that in the application of torsion to a sack constructed of any of these materials, it is tension and 95 not shearing stress that predominates, it becomes apparent that great pressure may be applied torsionally to the sack without rupturing the same, so that the container may be used directly as a grease gun in forcing 100 the grease into bearings or other places. Thus my dispensing container functions as a combined container and grease gun, thereby avoiding the messy condition attending the transfer of grease from an ordinary can 105 to the barrel of a separate grease gun.

In such attempts as have heretofore been made to apply the torsional principle of expulsion to inelastic containers, means had to be provided to compensate for the shortening of the sack in the direction of the axis of twist. These means sometimes included a spring by which the bottom of the sack was attached to the lower rigid member. In such cases when the sack is twisted the 115 spring elongates. Furthermore, it was thought that the torsional member could not be practically applied to a cylindrical sack on account of the formation of a twist at both ends imprisoning the contents, so that 120 in experimental attempts heretofore made, the sack has been made conical, or smaller at the bottom than at the top. I have avoided the complication and expense inherent in the use of springs or other compensating 125 devices, and the inefficiency due to loss of space where the sack was made smaller at one end than at the other, by making the sack of a transverse dimension substantially as great or greater than the length of the 130

axis of twist. The additional material required for the twist is then derived by drawing in the side walls of the sack and not by drawing upon the top and bottom walls, as 5 has been the case in former constructions.

In Figure 4 I have shown a slightly different form of the invention in which the excess in the transverse dimension of the sack over the length of the torsional axis thereof is 10 emphasized, the only other difference between this form and that previously described being in the means for securing the open mouth of the sack to the nozzle. In the present instance the nozzle 14 is made integral 15 with the top member 1 and the mouth of the sack is brought up inside of the nozzle and is clamped to the inner wall of the nozzle by an expandible ring 15.

The filling of both forms of collapsible 20 container may be advantageously accomplished by forcing the contents thereof through the nozzle while the sack is in a completely flat and collapsed condition. The sack expands under the pressure of the 25 contents, excluding air spaces and pressing the outer surface of the sack into contact with the walls of the chamber within the rigid members, causing it to adhere to the adhesive coating with which said walls have 30 been treated.

A form of the invention is shown in Fig. 6 in which the sack is inverted so that an imperforate portion 16 thereof occurs in registry with the nozzle, making the container self-sealed when assembled. Before expelling the contents from this sack, the imperforate portion 16 must be punctured by the user in any suitable manner. In securing the sack to the lower member 2, it is 40 first filled, then the mouth portion is drawn through a slot 17 formed in a disk 18, said disk being then riveted to the bottom of the member 2 at separate points 19 and 20 with the marginal edges of the sack clamped 45 in leak-proof manner between said sack. This insures against a pivotal movement taking place between the sack and the lower member. Means other than the disk 18 may be employed for securing the sack to said 50 lower member. It is of course understood that, at the time the sack is filled and attached to the member 2, it is of elongated shape so as to permit access of a riveting machine to said disk for the purpose of riveting the latter in place. The shape of the sack is finalized only when it is compressed 55 between the upper and lower members 1 and 2 in the act of assembling the container.

In Figure 8 I have shown an embodiment 60 of the invention in which the sack-housing chamber is formed entirely of a single member, designated by the reference character 21, the lower part only of which is shown. The bottom of said member is apertured for 65 the insertion of the shank of a key 22, which

corresponds functionally with the lower part 2 of the previously described form of the invention and is swivelly connected to the bottom of the member 21. Said key is preferably formed with an elongated slot 23 into 70 which the marginal edges of the mouth of the sack are inserted, the sides of the slot being then mashed together to seal the mouth of the sack and hold it against pulling away when the key is rotated. The 75 bottom of the member 21 is preferably dished to make room for the key so that the container may rest upon a flat base.

In all forms of the invention it is preferred that the sack be attached adhesively 80 to the side walls of the enclosing rigid member to obtain the advantages hereinbefore ascribed to this construction.

While I have herein described what I believe to be practical applications of the inventive principle, it is to be understood that numerous alternative constructions and arrangements of parts may be resorted to without violating the spirit or scope of the invention as defined in the appended claims. 85 90

Having described my invention what I claim as new and desire to secure by Letters Patent, is:—

1. A dispensing container including relatively rotatable rigid members, a torsionally 95 collapsible sack arranged between said members and fixed direct to each at its top and bottom, said sack having an axial dimension less than its dimension in a plane transverse to its axis, and being adapted to discharge 100 its contents through an aperture suitably formed in one of said members.

2. A dispensing container including relatively rotatable rigid members, a torsionally 105 collapsible sack arranged between said members and firmly secured to each at its top and bottom substantially in the line of axial twist of said sack, one of said members being hollow to receive said sack and means detachably securing said sack to the interior 110 of said hollow member and serving, while said members are relatively rotated, to prevent torsional stress upon the sack at the point at which said sack is firmly secured to said hollow member, until the sack is substantially collapsed, said sack being adapted 115 to discharge through an aperture suitably formed in one of said rigid members.

3. A dispensing container including relatively rotatable rigid members, a torsionally 120 collapsible sack arranged between said members and firmly secured to each at its top and bottom substantially in the line of axial twist of said sack, one of said members being hollow to receive said sack, the latter being 125 adhesively bonded in a lateral zone to said hollow member, said bond progressively yielding to torsional stress, beginning at the lower edge of said bonded zone, when said rigid members are relatively rotated, there- 130

by relieving the point at which said sack is firmly secured to said hollow member from torsional stress until the sack is substantially collapsed, said sack being adapted to discharge through an aperture suitably formed in one of said rigid members.

4. A dispensing container including co-operating relatively rotatable members, a torsionally collapsible sack between said members, secured to one member by an adhesive bond, and means constructed to seal the mouth of said sack and to secure it to the other member, to impart torsional stress to said sack when said members are relatively rotated, said sack being adapted to discharge through an aperture suitably formed in one of said rigid members.

5. A dispensing container including co-operating relatively rotatable members, one being hollow and having a discharge nozzle, a torsionally collapsible sack between said members having an imperforate portion thereof confronting said nozzle and secured to the inner wall of said hollow member by adhesive bond, and means constructed to seal the mouth of said sack and to secure it to the other member to impart torsional stress to said sack when said members are relatively rotated, said bond yielding progressively beginning at the lower edge thereof.

In testimony whereof I have hereunto set my hand.

WILLIAM H. G. GEAKE.
